UNITED STATES PATENT OFFICE.

ALBERT S. CARMAN, OF NEW YORK, N. Y., AND JOSEPH A. PERIN, JR., OF EAST ORANGE, NEW JERSEY.

MUFFLER ATTACHMENT FOR TELEPHONES.

Application filed June 7, 1924. Serial No. 718,455.

To all whom it may concern:

Be it known that we, ALBERT S. CARMAN and JOSEPH A. PERIN, Jr., citizens of the United States, and residents, respectively, of 5 New York, in the county of New York and State of New York, and of East Orange, in the county of Essex and State of New Jersey, have invented certain new and useful Improvements in Muffler Attachments for Telephones, of which the following is a specification.

This invention relates to devices for rendering telephone conversations inaudible to persons in the neighborhood of the transmitting telephone.

The invention includes a sound receiving and amplifying device designed to be attached to a standard telephone mouthpiece. The device is itself equipped with a mouthpiece into which the user may talk without possibility of his conversation being overheard by persons nearby. An expanding formation of the inner wall of the device from the mouthpiece to the telephone provides a sound amplifying function which permits the employment of a relatively low voice on the part of the speaker.

Another feature of the invention resides in the provision of a double wall construction providing an annular air chamber which acts as a sound insulating means and which communicates with the interior of the device and the surrounding air to form a tortuous passage which will permit fluctuations of air into and out of the device and at the same time prevent the escape of sound waves.

Other features of the invention include the ready removability of the muffling attachment from operative position through the use of a telescopic or slip joint connection.

In the drawings, in which a preferred form of the invention has been selected for illustration,

Figure 1 is a view in side elevation of a sound silencing attachment embodying the invention.

Figure 2 is a view in vertical section of 50 the device shown in Figure 1.

Referring to the drawings for a more detailed description of the invention, a standard type of telephone transmitter is shown at 10 and is supplied with the usual mouthpiece 11 projecting horizontally therefrom.

The present invention includes an attachment formed to be mounted in enclosing engagement with the telephone mouthpiece 11 at one end and projecting horizontally therefrom to provide a tubular member or 60 casing through which speech is conveyed from the attachment mouthpiece 12 to the telephone mouthpiece 11.

In order that a person using the telephone 12 may talk without his speech being overheard by persons nearby, the mouthpiece 12 is provided into which the lips of the user are pressed in the course of conversation. In order to insure the muffling or silencing of the speech to a sufficient degree to prevent its being overheard by unauthorized persons, the silencing device is formed with a double wall consisting of an inner wall 13 and an outer wall 14 spaced apart to provide an annular air chamber 15 wholly enclosing the side walls of the inner speech conveying tubular member 13. In order to permit the user to employ relatively low tones in talking into the mouthpiece 12, the inner tubular member 13 is given an expanding formation from the region of the mouthpiece 12 to its other end 16 adjacent the telephone mouthpiece 11. The effect of the expanding formation of the tubular member 13 is to amplify the sound waves 80 received therein and to thereby deliver to the mouthpiece 11 of the telephone sounds whose loudness has been increased between their point of reception at the mouthpiece 12 and the transmission to the telephone 90 mouthpiece 11.

The provision of the air chamber 15 in enclosing relation to the amplifying sound wave conveying member 13 not only acts as a muffler or silencer with relation to the sound conveying member 13 but by the provision of openings 17 in the inner member near one end thereof and openings 18 in the outer wall member 14 adjacent the opposite end of the chamber 15 any tendency that would otherwise be present to deaden or distort the speech is overcome since the openings 17 and 18 permit the oscillation of air into and out of the interior of the speech conveying member 13 to maintain a balance of pressure within and without the chamber. This prevents fluctuations of pressure within the member 13 which would interfere with the free propagation of speech. At the same time the placing of the openings 105 110

17 out of alinement with each other provides a relatively tortuous passage through which the air must fluctuate and in this way prevents the escape of sound waves from 5 the interior of the member 13 to the external air.

Another feature of the invention resides in the particular construction of the silencing attachment which provides for the removal of the silencing device from its position with a minimum amount of trouble. This is accomplished by providing telescopic connection as at 19 between the main part of the attachment and the right-hand 10 section 20 thereof which is reduced at one end to hold an annular cushioning member 21 which fits the external surface of the telephone mouthpiece 11 and serves as a support for the silencing attachment proper. 15 By this construction it will be seen that the sound silencing device can be readily slipped from its position in the outer end of the supporting member 20 whereupon the telephone may be used in the ordinary way 20 without resort to the silencing device. 25

What we claim is:—

1. In a device for preventing the unauthorized overhearing of telephone conversations, a supporting member having enclosing and cushioning engagement with the transmitter mouthpiece of a standard telephone, a voice transmitting and amplifying member of expanding formation having a readily detachable slip-joint connection with 30 said supporting member, the outer end of the amplifying member being provided with 35

a mouthpiece, a casing enclosing the amplifying member and spaced therefrom to form a sound insulating chamber surrounding the amplifying member, said amplifying member being provided with ports adjacent the mouthpiece and said casing being provided with a port adjacent the point of connection with the supporting member, said ports being in unaligned position whereby to provide a tortuous passage which will trap sound waves but permitting fluctuations of air pressure to pass into or out of the amplifying chamber. 40 45

2. In a device for preventing the unauthorized overhearing of telephone conversations, a two-part shielding device comprising a support adapted to have a cushioned and air-tight enclosing engagement with the transmitting mouthpiece of a standard telephone, and a sound amplifying part having a readily detachable slip-joint connection with the supporting member at its enlarged end, a substantially cylindrical casing enclosing said amplifying part and spaced therefrom to form a sound insulating chamber surrounding the amplifying part, the smaller end of the amplifying part being provided with a mouthpiece, said amplifying part being provided with ports adjacent said mouthpiece, said casing being provided with ports adjacent said joint, and said casing having a constricted formation adjacent said mouthpiece to facilitate the use of the mouthpiece. 50 55 60 65
